UNITED STATES PATENT OFFICE.

FRANK B. BOWER, OF PHILADELPHIA, PENNSYLVANIA, ASSIGNOR TO PHI KAPPA SIGMA FRATERNITY, OF PHILADELPHIA, PENNSYLVANIA.

DESIGN FOR A BADGE.

No. 38,180.

Specification for Design.

Patented July 24, 1906.

Application filed March 15, 1906. Serial No. 306,302. Term of patent 14 years.

To all whom it may concern:

Be it known that I, FRANK B. BOWER, a citizen of the United States, and a resident of Philadelphia, State of Pennsylvania, have invented a new, original, and ornamental Design for a Badge, of which the following is a specification, reference being had to the accompanying drawings, forming a part thereof. In the drawings, Figure 1 is a front view, and Fig. 2 is a side view, of a badge embodying my invention.

I claim—

The ornamental design for a badge, as shown.

FRANK B. BOWER
